CARTON ERECTING MACHINE

Edwin H. F. Mobley, deceased, late of Sodus, N. Y., by
Frances M. Mobley, administratrix, Sodus, N. Y., assignee to Bloomer Bros. Company, a corporation of
New York

Application September 15, 1951, Serial No. 246,846

15 Claims. (Cl. 93—37)

This invention relates to machines for automatically setting up or erecting collapsible cellular cartons made of cardboard or the like, such as egg boxes of the type having collapsible side wall and transverse cell-forming partitions. Such cartons are commonly made, stored and shipped in compact, collapsed condition and require setting up to prepare them for filling with eggs. The manual erection of such cartons for filling is a tedious, time-consuming step where they are handled in quantity lots. Devices are known without movable parts, or having parts movable only by hand, for assisting in the erection of such cartons but they have proven slow in operation for rapidly erecting a large quantity of cartons. Motor driven automatic machines for this purpose are known but they have been complicated and expensive to manufacture and maintain in operation. One object of the present invention, therefore, is to provide an improved machine of this character having a more simple, practical and efficient type of construction.

Another object is to produce such a machine in which the means for erecting the carton parts serves also to withdraw the cartons, one at a time, from a supply hopper, thus eliminating the necessity for carton feeding means.

Another object is the provision of such a machine in which the transverse partitions are erected and the carton is rapidly set up by continuously rotating parts.

Another object is to afford a machine of the character described so constructed that the completed cartons are discharged by the erecting mechanism without the necessity for stripping devices.

Another object is to provide a machine embodying a combination of the above advantages in a construction which is capable of being readily manufactured, assembled and maintained in uninterrupted operation at a relatively low cost.

To these and other ends the invention resides in certain improvements and combinations of parts, all as will be hereinafter more fully described, the novel features being pointed out in the claims at the end of the specification.

In the drawings:

Fig. 1 is a side elevation of an erecting machine embodying the present invention;

Fig. 2 is a side elevation similar to Fig. 1, but as viewed from the opposite side of the machine;

Fig. 3 is a top plan view of the machine;

Fig. 4 is an enlarged fragmentary perspective view showing the gripping means in position for partially removing the outermost carton from the hopper;

Fig. 5 is a similar to Fig. 4, but shows the carton partially removed and partially distended;

Fig. 6 is similar to Fig. 5, but shows the carton more fully distended and a rotary erecting device in position for engaging the carton;

Fig. 7 is similar to Fig. 6, but shows the carton more fully distended and the erecting device in position for fully erecting the transverse cell partitions and for partially moving the carton out of the hopper;

Fig. 8 is an enlarged sectional elevation of the erecting device in full engagement with said carton, but before the erection of the same;

Fig. 9 is similar to Fig. 8, but shows the erecting device in position for completing the setting up of the carton;

Fig. 10 is a sectional elevation of the erecting device along the line 10—10 in Fig. 8;

2

Fig. 11 is a sectional elevation of the erecting device along the line 11—11 in Fig. 8;

Fig. 12 is an end elevation of the carton gripping mechanism detached for purposes of illustration, and

Fig. 13 is an enlarged fragmentary, perspective view of one of the carton gripping vacuum cups.

The preferred embodiment of the invention, herein disclosed by way of illustration, is especially adapted for use with cellular cartons such as egg cartons which are commonly made of a one-piece blank of material cut, scored and folded to form two rows of six cells each. Such a carton comprises a front wall 18 (Fig. 4), a rear wall 20 (Fig. 6) and a central longitudinal partition 22 made by folding up portions between the bottom sections 24 (Fig. 6) and 26 (Fig. 5). A top wall indicated generally at 28 (Fig. 5) is connected with the tops of the front and rear walls and is cut and scored to form a series of transverse partitions indicated generally at 30, (Fig. 8) hinged to swing from a horizontal to a vertical position to fully erect the carton and separate the cells of each row. Rear wall 20 has hingedly attached thereto a cover portion 32 (Fig. 4) having a series of locking tabs along the free edge thereof.

The erecting machine preferably comprises a frame shown generally at 34 (Fig. 1) which has mounted adjacent one end thereof a trough-like rack or hopper shown generally at 36 for supporting a stack of collapsed or flattened cartons shown generally at 38. The cartons are partially distended and partially removed from hopper 36, as shown in Figs. 5 and 6, by an oscillating gripping mechanism shown generally at 40 (Figs. 2 and 12). The gripping mechanism positions the outermost carton for engagement by one of a pair of erecting devices shown generally at 42 (Figs. 1 and 2) which are mounted on the opposite sides of a rotatable erecting means shown generally at 44. Each erecting device is adapted to completely erect a carton, remove it from the hopper and deposit the same on a discharge conveyor

shown generally at 46 (Fig. 1). The machine is also preferably provided with a movable bottom supporting mechanism shown generally at 48 (Fig. 1) which is adapted to move a supporting member 50 (Fig. 6) into position for supporting the bottom of the carton during the distension and erection of the same as shown in Figs. 5 and 6.

The frame 34 of the erecting machine preferably comprises a pair of spaced parallel side members 52 of angle iron or other known and suitable material and a second pair of spaced parallel end members 54 of similar construction. Members 52 and 54 are fastened together to form an open framework or shelf 56 (Fig. 1) and are supported at the corners thereof by legs 58 (Fig. 1) of angle iron or other suitable material. Frame 34 is also provided with a second, open-centered platform or shelf 60 which is adapted to support an electric motor 62 (Fig. 1) and other components of the machine, as hereinafter more fully described.

Hopper 36 preferably comprises an inclined bottom member 64 (Fig. 3) which has attached to the opposite sides thereof side rails or members 66 (Figs. 1, 2 and 3). A pair of upright posts 68 (Fig. 4) are fastened to the lower ends of side members 66, as shown in Fig. 4, and have attached thereto a horizontally extending stop bar 70. Bar 70 is adapted to engage the inside of the cover portion 32 of the outermost carton, as shown in Figs. 4 and 5 and, together with a movable retaining finger 72, a fixed finger 74 (Fig. 4), and an upwardly projecting lip (not shown) on the bottom front edge of the hopper, is adapted to releasably hold the cartons in position in hopper 36, as hereinafter described. Hopper 36 is supported at the forward end thereof by a transversely extending bracket 76 (Fig. 1) which is attached to upwardly extending posts 68 by a pair of arms 78 (Figs. 3 and 4). The opposite end of the hopper is supported in an inclined position by a suitable bracket 80 (Fig. 1). The hopper may also be provided with a switch (not shown) of known and suitable construction, actuated by the weight of the collapsed cartons in the hopper and arranged to automatically open the electri-

cal circuit to motor 62 as the last carton is removed from said hopper for stopping the erecting machine.

The gripping mechanism preferably comprises a pair of vacuum or suction cups 82 (Figs. 4, 12 and 13) of known or suitable construction which are mounted on the top of a frame 84, as shown in Fig. 12. The lower portion of frame 84 is pivotally mounted on a transversely extending shaft 86, which in turn is supported at the opposite ends thereof in suitable bearings 88 on lower platform 60 as shown in Figs. 2 and 12. The top of frame 84 comprises two inwardly extending sections 90 and 92, the inner ends of which are spaced apart and have mounted thereon rollers 94 as shown in Fig. 12. Rollers 94 are adapted to engage a pair of grooves or cam tracks 96 which are located on opposite sides of the rotary erecting means 44, as shown in Figs. 1 and 2, and by means of which the gripping mechanism is caused to move between its rearward position shown in Figs. 1 and 2, and its forward position shown in Fig. 4. A spring 98 (Fig. 2) normally urges the mechanism to its rearward position.

As shown in Fig. 2, vacuum cups 82 are preferably connected by conduits 100 to a suitable low-pressure source such as an evacuating pump 102 mounted on lower platform 60. Pump 102, of known and suitable construction, has an inlet filter 104 and an outlet oil trap 106, both of known and suitable construction and which form no part of the present invention. Conduits 100 are connected to inlet filter 104 by a single conduit 108 and a by-pass valve 110 which is normally held in its closed position by a spring 112 so that a partial vacuum is maintained in cups 82 and conduits 100 and 108. Thus, when gripping cups are brought into engagement with the front wall of the outermost carton (Fig. 4) said cups firmly adhere to the front wall and pull said wall outwardly relative to the rear wall of the carton, past retaining fingers 72 and 74, as shown in Figs. 5 and 6 and as hereafter more fully described, as the gripping mechanism moves towards its rearward position shown in Figs. 1, 6 and 7. However, when the gripping mechanism reaches its rearward position, as shown in Figs. 1 and 2, one of the erecting devices is moving into erecting engagement with the partially distended, outermost carton, as shown in Fig. 6, and it is necessary to release the grip of cups 82 on the front wall of the carton so that the carton may be moved downwardly and to the left during the erection and withdrawal of the same from hopper 36. The means for releasing the grip of cups 82, preferably comprises a release lever 114 mounted on shaft 86. As the gripping mechanism moves towards its rearward position shown in Fig. 1, lever 114 is rotated in a clockwise direction, as viewed in Fig. 1, and an adjustable stud 116 attached thereto strikes against the lower portion of the valve stem and opens valve 110 against the tension of spring 112. This allows the pump to draw air in around said valve and breaks the partial vacuum in cups 82. Stud 116 may be adjusted to secure the proper timing between the release of cups 82 and the movement of the erecting device 42 into engagement with the outermost carton.

The rotary erecting means which, as shown in Fig. 6, engages the partially distended carton and erects or distends the same, preferably comprises a central member 118 (Fig. 2) having a pair of oppositely extending arms 120 which have mounted on the ends thereof the erecting devices 42, as shown in Figs. 1 and 2. Member 118 is mounted on a transversely extending shaft 122, the opposite ends of which are rotatably supported in suitable bearings 124, mounted on frame members 52 as shown in Fig. 3. Shaft 122 has adjacent the right end thereof, as viewed in Figs. 3-7, a sprocket 126 which is connected by a chain 128 to a suitable power source as hereafter described. Shaft 122 has a similar sprocket located adjacent the opposite end thereof by means of which the bottom supporting mechanism 48 is actuated in synchronism with the movement of the erecting devices 42 as hereinafter described.

Central member 118 has on opposite sides thereof a plate 130 (Fig. 7) of steel or other suitable material in which are formed grooves or cam tracks 96. Tracks 96 are substantially formed in the shape of an hourglass, as shown in Figs. 1 and 2 and are adapted to be engaged by rollers 94 mounted on the top of gripping mechanism frame 84. Thus, it will be seen that as shaft 122 and plates 130 are rotated, gripping mechanism 40 is caused to oscillate between its rearward position shown in Fig. 1, and its forward position shown in Fig. 4, for engaging and

partially distending the outermost carton, as shown in Figs. 5 and 6 and for positioning said carton for engagement with erecting devices 42 as hereafter more fully described.

5 Erecting devices 42 are preferably similar to the carton erecting devices disclosed in my copending application, Device for Setting Up Collapsible Cellular Cartons, Serial No. 113,079, filed August 30, 1949, now U. S. Patent No. 2,586,551, to which reference may be had for 10 a more complete disclosure of a preferred form of the erecting devices and certain constructional features herein disclosed but not claimed. Erecting device 42, similar to the devices disclosed in said copending application, 15 comprises a two-piece base having a stationary and a movable section 132 and 134, respectively (Fig. 9).

Stationary base section 132, as shown in Figs. 8 and 9, is fixed by screws 136 to a rectangular plate 138 which is formed with a longitudinally extending groove or track 140. Plate 138 is fastened by suitable means to the outer 20 end of arm 120 which has attached thereto a transversely extending flat bar 141 (Figs. 5-9). Right hand base section 134 is secured to an elongated bar 142 which is adapted to slide in said track and by means of which base portion 134 is moved from its position shown in Fig. 8 25 away from stationary base portion 132 to its position shown in Fig. 9. Base sections 132 and 134 are provided with a series of pairs of longitudinally spaced blades or fingers 144 and 146 (Figs. 8 and 9), respectively, which are adapted to engage the transverse cell partitions of the 30 partially distended carton as shown in Fig. 6. The blades are preferably formed in two rows, spaced apart adjacent the center of the base sections, as at 148 (Fig. 2), to accommodate the longitudinal partition 22 of the carton. As the rotary device is moved from its position shown in Fig. 6 towards its position shown in Fig. 7, said blades enter the carton and swing the transverse cell partitions to their partially erected position as shown in Fig. 8. The outermost pair of blades in each group or series of blades is preferably at substantially right angles to the remaining pairs of blades, as shown in Fig. 3, for insuring full 35 and complete erection of the ends of the carton.

To complete the erection of the transverse partitions, it is necessary to move right hand base portion 134 to the right relative to stationary base portion 132. This 40 movement first swings the right hand group of partitions 150, as viewed in Figs. 8 and 9, in a counter-clockwise direction to their fully erected position at which point their pivotal movement is arrested by engagement with shoulders 152 in the notches formed to accommodate them in the longitudinal partition. Rod 142 and base portion 134 are then moved further to the right, and as the right hand group of partitions cannot move relative to the carton, the entire carton is carried to the right so as to bring the left hand group of partitions 154 against stationary 45 blades 144, thus similarly swinging these partitions to vertical position against their stop shoulders 156 on the longitudinal partition as shown in Fig. 9 and as more fully described in my copending application. This shifting or moving of the carton relative to the fixed base portion 50 may be clearly seen by a comparison of Figs. 6 and 8, and Figs. 7 and 9, respectively.

It is to be noted that the rear wall of the carton is moved out of engagement with retaining fingers 72 and 74, as shown in Fig. 6, prior to the engagement of the 55 carton by the erecting device, as hereafter more fully described. Thus, the erecting device can readily move the carton sideways, relative to hopper 36, for completing the erection of the same, and can also carry the erected carton downwardly through its position shown in Fig. 7, 60 cover 32 freely sliding under stop bar 70, until the carton is completely removed from hopper 36, after which it is deposited on discharge conveyor 46 as hereafter described.

The means for moving rod 142 and base portion 134 to the right, comprises a cam 158 (Figs. 3, 8 and 9) and a roller 160 mounted on the left end of said rod. Cam 158 65 is preferably so shaped and positioned that roller 160 engages the upper portion 162 thereof as the erecting device fully engages the partially erected carton as shown in Fig. 8. As the erecting device is carried towards its position shown in Fig. 9, roller 160 moves downwardly along inwardly inclined cam surface 162 thereby moving rod 142 to the right and fully erecting the carton, as described above.

Cam 158, below surface 162, is preferably inclined 70 slightly to the right as at 164. The lowermost portion

of cam 158 is inclined outwardly to the left as at 166. Roller 160 engages inwardly inclined portion 164 after the carton has been fully erected, moving base portion 134 slightly to the right relative to fixed portion 132, and as a result the erected carton is securely gripped by the erecting device so that it may be easily carried downwardly out of hopper 36 and deposited on discharge conveyor 46. When roller 160 passes the lowermost portion 166 of the cam, it moves outwardly, under the action of a spring 168 (Fig. 9), carrying base portion 134 to the left towards stationary base portion 132, thereby releasing the carton from the erecting device, and allowing the same to fall by gravity onto discharge conveyor 46 or a curved feed plate 170 thereof (Fig. 1). Spring 168 which moves rod 142 and base portion 134 to their normal positions, as shown in Fig. 8 is secured at one end to plate 141 and at the other end to base portion 134, as shown in Figs. 8 and 9.

The present machine is readily adapted for use with a slightly modified type of carton in which the carton blank is scored transversely so that the carton may be readily torn in halves, each containing but six cells. In this type of carton, each half comprises two transverse partitions swinging in one direction and two partitions swinging in the opposite direction. Accordingly the erecting devices are provided with two stationary and two movable base sections arranged in alternate order starting on the left, as viewed in Fig. 8, with a stationary section. Each base section has two pairs of spaced, upwardly projecting fingers or blades, similar to blades 144 and 146, for erecting the transverse cell partitions of the carton in the same manner as described above for the non-divisible type of carton and similar to the method of operation set forth in detail in my said copending application.

The bottom supporting mechanism 48 preferably comprises a pair of arms 172 (Fig. 1) which are pivotally mounted on a transversely extending shaft 174 (Fig. 3) and which have at the forward ends thereof a transverse member 176 (Fig. 8) to which is attached bottom supporting member 50 (Fig. 1). Arms 172 are preferably shaped, as shown in Figs. 1-3, and are connected together at the opposite ends thereof by a short shaft 178 (Fig. 3) which is engaged by a cam 180 (Fig. 2) mounted on a transversely extending shaft 182 (Fig. 3) the opposite ends of which are rotatably supported in suitable bearings 184 mounted on upper frame members 52. In order to insure proper coordination between the bottom supporting member 50 and the movement of the erecting devices 42, shaft 182 has a sprocket 186 (Fig. 1) adjacent one end thereof, which is connected to a similar sprocket 188 on shaft 122 by a chain 190 (Fig. 1). The rotation of shaft 182 and cam 180 causes arms 172 to oscillate between their raised and lowered positions, as shown in Fig. 2, by full and broken lines, respectively. When arms 172 move to their uppermost position, transverse supporting member 50 is moved into position for supporting the bottom of the outermost carton during the distention of the carton by gripping mechanism 40, and during the first stages of the erection of the carton by one of the erecting devices 42, as shown in Figs. 8 and 9. Cam 180 is so shaped that supporting member 50 moves downwardly with the carton during the completion of the erection of the same by erecting device 42, as shown in Figs. 6-9. After the carton is fully erected, as shown in Fig. 9, supporting member 50 quickly moves out of engagement with the carton and into its lowermost position, as shown in Fig. 2, thereby allowing the carton to be fully removed from the hopper and deposited upon conveyor 46 by the erecting device as described above.

Discharge conveyor 46 preferably comprises a rectangular frame 192 (Figs. 1 and 3) having at the opposite ends thereof a pair of transversely extending shafts 194 which have pulleys 196 mounted thereon. Corresponding pulleys on shafts 194 are connected together by belts 198 of rubber or other known and suitable material forming an endless conveyor belt so that as said shafts and belts are driven in a clockwise direction, as viewed in Fig. 1, any cartons deposited on the lower end of the conveyor will be carried by friction upwardly and to the right on the upper surface of the belts for clearing the erecting machine of the erected cartons.

The carton retaining means which comprises stop bar 70, stationary retaining finger 74, movable retaining finger 72, and a small upwardly projecting lip or plate (not

shown) adjacent the lower front edge of hopper 36, is adapted to provide a positive means for holding a stock of cartons in the hopper and yet at the same time allow the cartons to be removed, one at a time, for erection, without the tearing of the same.

The means for moving retaining finger 72 (Fig. 4) to release the outermost carton for erection, preferably comprises a solenoid 200 having an armature 202 which is connected at the outer end thereof to finger 72. Armature 202 and finger 72 are yieldably held in their positions shown in Fig. 4 by a coil spring 204. When the front wall 18 of the outermost carton is moved by gripping mechanism 40 from its position shown in Fig. 4 to its position shown in Fig. 5, front wall 18 and central longitudinal partition 22 are pulled past an upwardly projecting lip (not shown) on the bottom front edge of the hopper, and past movable finger 72 and stationary finger 74, the latter two of which then engage the inner surface of rear wall 20 of the outermost carton. Gripping mechanism 40 continues to move the front wall of the carton away from the rear wall which is prevented from moving outwardly by fingers 74 and 72, thereby partially distending the carton. As the front wall reaches its fully extended position, solenoid 200 is connected to a suitable source of electrical energy by the closing of a switch 206 (Fig. 2). The energization of solenoid 200 draws armature 202 to the right, as viewed in Figs. 4-7, through a guide plate 208 (Fig. 4) and moves finger 72 out of contact with the rear wall of the outermost carton which then springs past finger 74 and moves outwardly away from hopper 36 under the action of gripping mechanism 40. The carton is then in position for engagement by one of the erecting devices, as shown in Fig. 6.

Switch 206 is closed for only a short period of time so that finger 72, under the action of spring 204, quickly returns to its normal position where it engages the outer surface of the front wall of the next succeeding carton and holds the remaining cartons in hopper 36, as shown in Fig. 6. Switch 206 is actuated by a diamond-shaped cam 212 (Fig. 2) mounted on the outer end of shaft 182 which rotates at the same speed as shaft 122 and erecting devices 42 so that switch 206 is closed each time one of the erecting devices is about to come into carton engaging position as shown in Fig. 6.

The erecting machine is provided with means for actuating and coordinating the movement of the rotary erecting devices, the vacuum gripping mechanism, the movable bottom supporting member, the releasable carton retaining mechanism and the discharge conveyor 46. Preferably, the power for actuating the above components is supplied by electric motor 62 which is connected by a suitable belt 214 (Fig. 1) to a pulley 216 (Fig. 1) attached to a speed reducing gear box 218 (Fig. 1) of known and suitable construction. Gear box 218 has a spur gear 220 and a sprocket 222 (Fig. 2) mounted on a shaft 224 (Fig. 2) which extends through the gear box, as shown in Figs. 2 and 3. Chain 128 connects sprocket 222 to a similar sprocket 126 on transverse shaft 122. The rotation of the shaft 122 not only rotates the carton erecting devices, but as shaft 122 is connected to shaft 182 by chain 190, it also causes shaft 182 to rotate at the same speed. As described above, cam 180 on shaft 182 controls the movement of the bottom supporting member and the diamond-shaped cam 212 which controls the release of the movable carton retaining finger 72. Thus, the movement of the erecting devices, the bottom supporting member, and the movable releasable retaining finger are all coordinated and synchronized one with the other and with the movement of the gripping mechanism 40 which is caused to move from its rearward position, as shown in Fig. 2, to its forward position, as shown in Fig. 4, by the rotation of cam tracks 96 which are engaged by rollers 94 on the gripping mechanism frame. Sprockets 226 (Fig. 1) and 228 (Fig. 2) serve as tightening means for chains 190 and 128, respectively, as well understood in the art.

Spur gear 220 engages a pinion 230 (Fig. 2) located adjacent one end of a transversely extending shaft 232 (Figs. 1 and 2) which is mounted in suitable bearings 234 (Figs. 1 and 2) on legs 58. Shaft 232 has a large pulley 236 (Fig. 1) adjacent the opposite end thereof which is preferably adapted for use with a V belt 238 (Fig. 1) or other suitable driving means which connects said pulley to a smaller pulley 240 (Fig. 1) on the lower shaft 194 of the discharge conveyor mechanism described

above. Thus, the discharge conveyor is also driven by electric motor 62, and to start the entire machine in operation it is only necessary to close the electrical circuit to motor 62 by a suitable, single switch (not shown).

In operation, therefore, a stack of collapsed or flattened cartons is placed in hopper 36 and as the erecting machine is operated, the gripping mechanism swings forward from its position as shown in Fig. 2 to its position as shown in Fig. 4 at which point the vacuum gripping cups are brought into engagement with the front wall of the outermost carton, and as said gripping mechanism returns towards its initial position shown in Fig. 2, the front wall of the carton is pulled outwardly from its position, as shown in Fig. 4, through its position shown in Fig. 5 to its position as shown in Fig. 6, at which point the carton is nearly distended and is supported by bottom supporting member 50. As the outermost carton is being distended or opened up, as shown in Figs. 4-6, one of the rotary erecting devices 42 moves from its position shown in Fig. 4, to its position shown in Fig. 6, at which point the erecting device is just moving into engagement with the top of the carton and is in position for completing the erection of the carton and for moving the carton downwardly out of the hopper, as shown in Fig. 7, and depositing the same on conveyor 46 by means of which the erected carton is removed from the machine. It will be noted that the vacuum cup and rotary carton erecting means serve also as the means for withdrawing the cartons from the hopper, thereby eliminating the necessity for carton feeding means for that purpose. The erection of the transverse partitions and the completion of the setting up of the carton is rapidly accomplished by the continuously rotating erecting devices 42 which furthermore operate to discharge the completed cartons, so as to obviate the necessity for carton stripping devices. These parts, of relatively simple construction, function effectively and reliably to withdraw the cartons from the hopper, erect them and discharge the completed cartons in a rapid and automatic manner, requiring the attention of an operator only to keep the hopper supplied with a quantity of cartons to be erected.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism for removing one of said cartons from said hopper and for partially distending said carton, rotary means entering said partially distended carton between the front and rear walls thereof and engaging and swinging the transverse members to erected position for fully erecting said carton, movable means for supporting the bottom of said partially distended carton during the erection of the same by said rotary means, and means for actuating said mechanism, said bottom supporting means and said rotary means in timed coordination with one another.

2. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism for removing one of said cartons from said hopper and for partially distending said carton, rotary means entering said partially distended carton between the front and rear walls thereof and engaging and swinging the transverse members to erected position for fully erecting said carton, movable means for supporting the bottom of said partially distended carton during the erection of the same by said rotary means, and means for continuously rotating said rotary means and for actuating said mechanism and said bottom supporting means in timed coordination with one another.

3. A machine for setting up collapsible cartons of the

type having front and rear walls hingedly attached to the opposite sides of the bottom wall and transverse members adapted to be swung at right angles to the bottom wall in setting up the carton, said machine comprising a hopper for supporting a stack of collapsed cartons, mechanism comprising oscillating gripping means for removing one of said cartons from said hopper and for partially distending the same, rotary means entering said partially distended carton between the front and rear walls thereof and engaging and swinging the transverse members to erected position for fully erecting said carton, movable means for supporting the bottom of said partially distended carton during the erection of the same by said rotary means, and means for oscillating said gripping means and actuating said bottom supporting means and said rotary means in timed coordination with one another.

4. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism comprising oscillating gripping means for removing one of said cartons from said hopper and for partially distending said carton, rotary means entering said partially distended carton between the front and rear walls thereof and engaging and swinging the transverse members to erected position for fully erecting said carton, movable means for supporting the bottom of said partially distended carton during the erection of the same by said rotary means, and means for continuously rotating said rotary means and oscillating said gripping means and actuating said movable means in timed coordination with one another.

5. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism for removing one of said cartons from said hopper and for partially distending said carton, rotary means having parts movable thereon entering said partially distended carton between the front and rear walls thereof and engaging and swinging the transverse members to erected position for fully erecting said carton, movable means for supporting the bottom of said partially distended carton during the erection of the same by said rotary means, means for continuously rotating said rotary means and moving said parts thereon to engage and erect said carton and to release and discharge the same and means for actuating said mechanism and said bottom supporting means in timed coordination with said rotary means.

6. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism comprising oscillating gripping means for removing one of said cartons from said hopper and for partially distending said carton, rotary means having parts movable thereon entering said carton between the front and rear walls thereof and engaging and swinging the transverse members to erected position to fully erect said carton, movable means for supporting the bottom of said partially distended carton during the erection of the same by said rotary means, means for continuously rotating said rotary means and moving said parts thereon to engage and distend said carton and to release and discharge the same and means for actuating said mechanism and said bottom supporting means in timed coordination with said rotary means and parts.

7. A machine for setting up collapsible cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, mechanism for partially removing the outermost one of said cartons from said hopper and for partially distending the same, rotary means entering said partially distended carton between the front and rear walls thereof and engaging and swinging the transverse members to erected position

for fully erecting said carton and for removing the same from said hopper, movable means for supporting the bottom of said partially distended carton during the erection of the same by said rotary means, movable retaining means for releasably holding said cartons in said hopper, means for moving said retaining means for releasing the outermost carton for removal by said mechanism and by said rotary means, and means for actuating said mechanism, said bottom supporting means, said rotary means and said moving means in timed coordination with one another.

8. A machine for setting up collapsible cartons having front and rear walls hingedly attached to the opposite sides of the bottom wall and transverse members adapted to be swung at right angles to the bottom wall in setting up the carton, said machine comprising a hopper for supporting a stack of collapsed cartons, vacuum gripping means for partially removing one of said cartons from said hopper and for partially distending the same, rotary means entering said partially opened carton between the front and rear walls thereof and engaging and swinging the transverse members to erected position for fully erecting said carton and removing the same from said hopper, movable means for supporting the bottom of said partially distended carton during the erection of the same by said rotary means, cooperating means connecting said vacuum means and said rotary means for synchronizing the movement of said vacuum means with said rotary means, movable retaining means for releasably holding said carton in said hopper, means for moving said retaining means for releasing the outermost carton for removal by said vacuum means and by said rotary means, and means for actuating said bottom supporting means, said moving means and said rotary means in timed coordination with one another.

9. A machine for setting up collapsible cartons having front and rear walls hingedly attached to the bottom wall along the opposite sides thereof and transverse members adapted to be swung at right angles to the bottom wall in setting up the carton, said machine comprising a hopper for supporting a stack of collapsed cartons, vacuum gripping means for partially removing the outermost one of said cartons from said hopper and for partially distending the same, rotary means entering said partially opened carton between the front and rear walls thereof and engaging and swinging the transverse members to erected position for erecting and removing said carton from said hopper, movable means for supporting the bottom of said partially distended carton during the erection of the same by said rotary means, cam means on said rotary means, roller means on said vacuum means engaging said cam means for swinging said vacuum means into gripping engagement with the front wall of the outermost carton in said hopper and for moving said vacuum means and the front wall of said carton away from said hopper for partially opening said carton as said rotary means moves into carton engaging position, and means for actuating said bottom supporting means and said rotary means in timed coordination with one another.

10. A machine for setting up collapsible cartons having front and rear walls hingedly attached to the bottom wall along the opposite sides thereof, said machine comprising a hopper for supporting a stack of collapsed cartons, vacuum gripping means for partially removing the outermost one of said cartons from said hopper and for partially distending the same, rotary means engaging said partially opened carton for distending and removing the same from said hopper, movable means for supporting the bottom of said partially distended carton during the erection of the same, cam means on said rotary means, roller means on said vacuum means engaging said cam means for swinging said vacuum means into gripping engagement with the front wall of the outermost carton in said hopper and for moving said vacuum means and the front wall of said carton away from said hopper for partially opening said carton as said rotary means moves into carton engaging position, movable retaining means for releasably holding said cartons in said hopper, means for moving said retaining means for releasing the outermost carton for removal by said vacuum means and by said rotary means, and means for actuating said vacuum means, said bottom supporting means, said rotary means and said moving means in timed coordination with one another.

11. A machine for setting up collapsible cartons hav-

ing front and rear walls hingedly attached to the opposite sides of the bottom wall, said machine comprising a hopper for supporting a stack of collapsed cartons, movable retaining means releasably engaging the front wall of the outermost carton for holding said carton in said hopper, vacuum gripping means for partially removing the outermost carton from said hopper and for partially distending the same, the front wall of said carton being moved out of engagement with the retaining means by said gripping means, rotary means engaging said partially opened carton for fully distending the same and for fully removing said carton from said hopper, movable means for supporting the bottom of said partially distended carton during the erection of the same, means for moving said retaining means out of engagement with the rear wall of said outermost carton as said gripping means partially removes said carton from said hopper, yieldable means for moving said retaining means into engagement with the front wall of the next succeeding carton for holding the remaining cartons in said hopper, and means for actuating said gripping means, said moving means, said bottom supporting means and said rotary means in timed coordination with one another.

12. A machine for setting up collapsible cellular cartons of the type having front and rear walls hingedly attached to the opposite sides of the bottom wall and transverse members adapted to be swung at right angles to the bottom wall in setting up the carton, said machine comprising a hopper for supporting a stack of collapsed cartons, vacuum means for partially removing one of said cartons from said hopper and for partially distending the same, rotary means engaging said partially opened carton for fully distending the same and for removing said carton from said hopper, movable means for supporting the bottom of said partially distended carton during the erection of the same, spaced blades mounted on said rotary means for engaging the transverse members for swinging said members to erected position, and means for actuating said vacuum means, said bottom supporting means and said rotary means in timed coordination with one another.

13. A machine for setting up collapsible cellular cartons having front and rear walls hingedly attached to the opposite sides of the bottom wall and transverse partitions hingedly connected to the tops of the front and rear walls and adapted to be swung from horizontal to erected vertical position, said machine comprising a hopper for supporting a stack of collapsed cartons, vacuum gripping means for partially removing one of said cartons from said hopper and for partially distending the same, rotary means engaging said partially opened carton for fully distending and removing the same from said hopper, movable means for supporting the bottom of said partially distended carton during the erection of the same, spaced blades mounted on said rotary means for engaging and partially erecting the transverse partitions as said rotary means engages said partially distended carton, cam means for moving said blades for swinging said partitions to vertical position to complete the erection of said carton, and means for actuating said gripping means, said bottom supporting means and said rotary means in timed coordination with one another.

14. A machine for setting up collapsible cellular cartons having front and rear walls hingedly attached to the opposite sides of the bottom wall and transverse partitions hingedly connected to the tops of the front and rear walls and adapted to be swung from horizontal to erected vertical position, said machine comprising a hopper for supporting a stack of collapsed cartons, vacuum means for partially removing one of said cartons from said hopper and for partially distending the same, rotary means engaging said partially opened carton for fully distending and removing said carton from said hopper, movable means for supporting the bottom of said partially distended carton during the erection of the same, spaced blades mounted on said rotary means for engaging and partially erecting the transverse partitions as said rotary means engages said partially distended carton, cam means for moving said blades for engaging and swinging said partitions to vertical position to complete the erection of said carton and for releasing and discharging the erected carton from the machine, and means for actuating said vacuum means and said bottom supporting means and for continuously rotating said rotary means in timed coordination with one another.

15. A machine for setting up collapsible cellular cartons of the type having front and rear walls, a central longitudinal partition and two groups of transverse partitions hingedly connected to the tops of said front and rear walls and adapted to be swung in opposite directions, respectively, from horizontal to erected vertical position, said machine comprising a hopper for supporting a stack of collapsed cartons, vacuum gripping means for partially removing one of said cartons from said hopper and for partially distending the same, rotary means engaging said partially opened carton for fully distending and removing said carton from said hopper, movable means for supporting the bottom of said partially distended carton during the erection of the same, said rotary means comprising two groups of spaced blades projecting therefrom for engagement with the partitions of said groups, respectively, for partially erecting the transverse partitions as said rotary means engages said partially distend-

ed carton, means for effecting the relative movement of said groups of blades in opposite directions to complete the erection of said partitions, and means for actuating said gripping means, said bottom supporting means and said rotary means in timed coordination with one another.
